(57) **CLAIM**

The ornamental design for a go-kart, as shown and described.

DESCRIPTION

FIG. 1 is a font perspective view of the go-kart;

FIG. 2 is a top plan view thereof;

FIG. 3 is a front elevation view thereof;

FIG. 4 is a bottom plan view thereof;

FIG. 5 is a left side elevation view thereof;

FIG. 6 is a rear elevation view thereof; and,

FIG. 7 is a right side elevation view thereof.

The broken lines shown in the drawings illustrate portions of the go-kart that forms no part of claimed design.
